(57) **CLAIM**

The ornamental design for wall shelf as shown and described.

DESCRIPTION

FIG. 1 is a front elevational view of a wall shelf, showing my new design;

FIG. 2 is a rear elevational view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front, left, and top perspective view thereof; and,

FIG. 8 is a rear, right, and top perspective view thereof.
